United States Patent Office.

GEORGE HERRICK, OF WAVERLY, NEW YORK.

Letters Patent No. 98,378, dated December 28, 1869.

IMPROVED RAILWAY-CAR TRUCK.

The Schedule referred to in these Letters Patent and making part of the same

To all whom it may concern:

Be it known that I, GEORGE HERRICK, of Waverly, in the county of Tioga, and State of New York, have invented a new and valuable Improvement in Attaching Car-Wheels to the Trucks; and I do hereby declare that the following is a full, clear, and exact description of the construction and operation of the same, reference being had to the annexed drawings, making a part of this specification, and to the letters and figures of reference marked thereon.

Figure 1, of the drawings, is a bottom view of my invention.

Figure 2 is a central longitudinal vertical section of same.

Figure 3 is a vertical cross-section of same.

Figure 4 is a top view of the slotted pedestal of same.

Figure 5 is a top view of bearing-plate, showing same.

My invention relates to means for attaching the wheels to the trucks of railroad-cars, and consists, mainly, in the construction and novel arrangement of devices, as hereinafter described, whereby each wheel is rendered capable of revolving independently, and also of taking a position on curves parallel to the rail.

The letter A, of the drawings, designates the truck-frame, supported on the rubber cushions v v by the plates B B, which rest on the pedestals C C.

The wheel D runs between the upright arms h h of each pedestal C, and its short axle a' finds its bearings in the lower portions of these arms.

The upper ends of the arms are connected by the plate c, to the centre of which is attached the swivel-pin e, which connects the pedestal to the plate B, and allows said pedestal to turn, thus enabling the wheels to take a position on curves parallel to the rails.

A nut, s, secures the top of the swivel-pin, which projects through the plate B.

A washer is used between the plates B and c on the pin e.

Near each end of the plate c, a curved slot, n, is formed, through which passes a pin, z, fixed to the plate B, thereby limiting the change of direction of the wheel.

To the lower end of the inner arm h of each pedestal C, which extends below the flanged end of the axle, is pivoted the end of a brace, H.

By means of these braces, each pedestal is connected to its opposite fellow, in such a manner as to assist materially in the preservation of its upright position. The wheels D D, also, are thereby kept at the proper distance from each other.

The position of the brace H below the axles gives it so much power that it supplies the place of the connecting-axle usually employed between the wheels.

The short axle a' of each car-wheel is grooved on each side of the wheel, to form the journals thereof.

What I claim as my invention, and desire to secure by Letters Patent, is—

1. In combination with the bearing-plate B of a car-truck, provided with the guard-pins z z, the swivel-pedestal C, pivoted to the plate B, said pedestals having curved slots, n n, and forming bearings for the journals of the car-wheel.

2. The car-wheel D, having grooved axle a', in combination with the swivel-pedestal C and pivoted brace H.

3. The car-truck herein described, having frame A, rubber cushions v v, bearing-plates B B, provided with pins z z, and pivoted to the slotted pedestals C C, braced by the pivoted bars H H, and forming bearings for the grooved axles a' a' of the car-wheels.

In testimony that I claim the above, I have hereunto subscribed my name, in the presence of two witnesses.

GEO. HERRICK.
